ERNEST ANDREW REID, OF LONDON, ENGLAND.

METHOD OF AND APPARATUS FOR ATOMIZING AND BURNING FUEL OIL.

Application filed February 2, 1922. Serial No. 538,645.

To all whom it may concern:

Be it known that I, ERNEST ANDREW REID, subject of the King of Great Britain, residing at London, England, have invented a certain new and useful Method of and Apparatus for Atomizing and Burning Fuel Oil, of which the following is a specification.

This invention relates to an improved method of and apparatus for atomizing and burning fuel oil, which is particularly suitable for burning heavy crude oils.

One difficulty in atomizing fuel oil which has been encountered, is the choking up or clogging of the small bores of the atomizing nozzles generally used. Among the objects of this invention is to produce an oil burner of simple construction in which the possibilities of interruption through clogging or choking are entirely eliminated, and with which perfect diffusion and combustion of the fuel is obtained. The invention, while particularly applicable for the thorough atomization of viscous oils, is not however, limited to atomizing heavy crude oils or oils of high viscosity.

According to the invention, the fuel oil is converted into a film or thin layer, which is allowed to fall over a lip, and is atomized by a plurality of converging jets of steam under pressure or compressed air, by which complete diffusion and vaporization of the fuel is obtained. The invention also consists in an apparatus having an oil supply pipe or the like, a distributing surface over which the oil is spread in a film, and a plurality of converging steam or compressed air jets adapted to atomize the film or thin curtain of oil as it falls from the distributing surface in front of the jets.

A particularly effective apparatus consists of a casing, which is preferably a one-piece casting, divided into an upper distributing chamber over the floor of which the oil is spread in a film, and a lower steam chamber.

The floor of the distributing chamber is provided with a lip over which the oil falls curtain-wise in front of a plurality of jets of steam under pressure or compressed air emerging from orifices in the front of the lower chamber and arranged to converge forwardly in pairs.

The invention will now be described with reference to the accompanying drawings,

which illustrate a preferred form of the apparatus. In these drawings;

Fig. 1 is a longitudinal median section of one example of construction of the apparatus;

Fig. 2 is a front elevation;

Fig. 3 is a sectional plan, taken on the line A—B of Fig. 2.

Fig. 4 is a front view of a plate having the converging atomizing orifices arranged in two horizontal rows, this plate when in position being fixed to the front of the lower chamber;

Fig. 5 is an edge view of the same plate as seen from below, showing the paths and points of intersection of the converging pairs of jets delivered from the orifices in the respective rows;

Fig. 6 is a portion on a much enlarged scale of the plate as seen from below in section on the line of the lower row of orifices.

The body of the atomizer illustrated in the drawings is fan-shaped in plan, and comprises preferably a one-piece casting having an upper distributing chamber 1 with an open front end, into which chamber oil is supplied through the opening 2 tapped to receive a pipe connection. The top 1^a of the chamber 1 may be arched, as shown in Fig. 2. 3 is the lower chamber, into which steam under pressure or compressed air is introduced through the opening 4.

5 is a partition that separates the two chambers 1 and 3; and its upper surface forms a distributing surface to spread the incoming oil. This distributing upper surface of the partition 5 is preferably horizontal below the opening or port 2, as indicated at 6, and then slopes downwards and forwards. It terminates at the delivery end in a lip 7 which inclines downwards more sharply than the sloping surface, the lip being preferably curved as shown. The lip is also preferably hollowed out at its under side, as at 7^a.

For the greater part of its length the inclined upper surface of the partition 5 is longitudinally grooved. As shown in the drawings, this surface is corrugated with ribs 8 and alternating grooves 9. These corrugations, which commence at the horizontal part 6 of the surface, gradually become wider and flatter as they extend down towards the lower or delivery end of the surface, and

finally disappear a short distance above the lip 7, as shown.

The grooving instead of being longitudinal could be transverse or otherwise, so as 5 to act to delay the oil flow and obtain a more effective distribution and heating of the oil. The upper surface of the partition may advantageously be transversely cambered and transversely grooved, the grooves 10 being deepest on the median line of the surface and becoming shallower towards the sides.

The front wall of the chamber 3 that receives the atomizing fluid is provided, below 15 and at the rear of the overhanging lip 7, with a series of orifices 10. These are arranged to converge in pairs so as to deliver jets towards points 11 which are approximately vertically beneath the edge of the lip 7 20 as clearly shown in Fig. 3. These orifices may be formed in a front wall of the chamber 3 integral with the body of the atomizer, but in the preferred construction the orifices 10 are formed in a separate plate 12, bolted on 25 by bolts 18 to the open front of the chamber 3. The top of this orifice-plate 12 takes into a recess 13 in a thickened part 13^a on the lower side of the forward end of the partition 5. The bolt-holes in the plate 12 30 coincide, of course, with corresponding tapped holes 14 in thickened parts or bosses 15 in the front of the body casting. Jointing material 16 is used to ensure a steam-tight joint. This provision of a removal 35 orifice plate is very convenient for purposes of repair or renewal.

In Figs. 1-3 the orifices are arranged in a single row. It is, however, preferred to provide a double row of orifices. In some 40 cases even three rows are necessary where very thick oils are used. In Figs. 4-6 I illustrate an orifice plate having the orifices arranged in two horizontal rows, the pairs 45 of converging orifices in the respective rows being arranged in staggered relationship. In Fig. 6 the orifices of the lower row are shown in full lines, while the orifices in the upper row are indicated by broken lines. Fig. 5 shows the convergence 50 of the pairs of jets to their points of intersection 11, through which points the oil film falls.

17 is an opening in the bottom wall 3^a of the chamber 3 for the reception of a cock for 55 draining off condensed steam when steam is used.

The atomizer may be fan-shaped in plan, as shown, and this form is especially adapted 60 for wide fire-box boilers. This burner increases the life of the fire-brick baffles, tube plate and walls of the firebox, owing to the practically perfect diffusion of the fuel which is the result of the disintegration of 65 a dropping film of oil, and the resultant sheet-form flame has not the destructive ef-

fects of the concentrated or jet flame. If desired, however, the apparatus instead of being fan-shaped, may be of a rectangular or other suitable form, which may be especially adapted for use in cases where the 70 burner has to operate in a narrow fire-box, such as the flue of a Lancashire or Cornish or marine boiler.

In operation, the oil supplied to the chamber 1 through the opening 2 spreads out 75 over the floor of the chamber 3, the area of the floor being increased by its corrugated structure. The oil flows outwardly over the floor 5 of the chamber 1 and on reaching the lip 7, falls over the lip a short distance 80 in front of the orifices 10 in the form of a thin curtain of a length corresponding practically to the length of the lip. Steam under pressure or compressed air from the chamber 3 emerges as converging jets from the 85 pairs of orifices 10, which jets break up against each other at their points of intersection on the line 11, and produce there a region of turmoil through which the film of oil falls, whereby the disruption and 90 complete atomization of the falling oil film are effected. By the described arrangement of the converging orifices in relation to the falling film of oil the most effective atomization is obtained.

In the case of very viscous oils, the spreading of the oil upon the floor of the oil-distributing chamber 3 is materially assisted by the heating due to the steam; and no matter how thick the oil, it flows freely 100 over the floor and out over the lip. This design of burner which incorporates a steam jacket below the chamber through which the fuel oil passes ensures an even flow of the oil even in the coldest of weathers. Of course, the oil may be pre-heated, if desired, before it is taken to the atomizer.

The apparatus ensures adequate atomization and diffusion of the oil, which, having 110 been converted into a film or thin layer, becomes disintegrated and diffused as it falls in front of the atomizing jets of steam or compressed air. Thus the oil is put into a good condition for combustion. Combustion takes place in the form of an evenly distributed sheet-flame across the whole width of the firebox, whereby the heat is thoroughly well and efficiently distributed, and the deteriorating effect of a concentrated 115 flame of the jet type is avoided, with a corresponding improvement in its effective heating capacity.

It will be seen that the apparatus is an 120 extremely simple and inexpensive one to manufacture, and there are no complicated fittings to get out of order. There is no possibility of clogging, and of course the atomizing orifices are kept clean naturally. The device is adaptable for any heating 125 service required even when using the heavy-

est and crudest grades of fuel oil. The apparatus is readily installed in connection with the fireboxes or combustion chambers of any make of boiler or heating furnace and may be made of any desired shape or size to meet the requirements of any kind of combustion chamber.

I declare that what I claim is:—

1. The method of atomizing fuel oil, which consists in distributing the oil in the form of a film and causing it to fall as a thin curtain in front of a plurality of converging jets of atomizing fluid under pressure.
2. The method of atomizing fuel oil, which consists in distributing the oil in the form of a film, heating the oil while in the form of a film, and causing this heated film of oil to fall as a thin curtain in front of a plurality of converging jets of atomizing fluid under pressure.
3. An apparatus for atomizing fuel oil, comprising a chamber; means for supplying the oil thereto; a surface on which the oil is spread in a film, a lip over which the oil film can fall, and a plurality of orifices below and behind said lip forwardly converging towards points approximately vertical beneath the edge of said lip, through which orifices jets of atomizing fluid under pressure are delivered to atomize the film of oil falling upon the points of intersection of said jets.
4. An apparatus for atomizing fuel oil, comprising a chamber; means for supplying the oil thereto; a surface on which the oil is spread in a film; a lip over which the oil can fall; and a plurality of orifices below and behind the said lip forwardly converging in pairs towards points approximately vertical beneath the edge of said lip, through which orifices jets of atomizing fluid under pressure are delivered to atomize the film of oil falling upon the points of intersection of said converging jets.
5. An apparatus for atomizing fuel oil, comprising a chamber; means for supplying the oil thereto; a surface on which the incoming oil spreads in a film; a lip over which the oil can fall in a thin curtain; and a plurality of horizontal rows of orifices which are arranged in pairs forwardly converging towards points approximately vertically beneath the edge of the said lip, the orifices in the respective rows being disposed in staggered relationship.
6. An apparatus for atomizing fuel oil comprising an upper and a lower chamber; means for supplying the oil to the upper chamber and steam under pressure or compressed air to the lower chamber; a floor on which the oil is distributed as a film; a lip at the edge of said floor over which the oil film can fall as a thin curtain and a plurality of converging orifices in the front
7. An apparatus for atomizing fuel oil comprising an upper and a lower chamber; means for supplying the oil to the upper chamber and steam under pressure or compressed air to the lower chamber; a floor on which the oil is distributed as a film; a lip at the edge of said floor over which the oil film can fall as a thin curtain; and a plurality of orifices forwardly converging in pairs towards points approximately vertically beneath the edge of the said lip, through which orifices jets of steam under pressure or compressed air are delivered to atomize the falling curtain of oil.
8. An apparatus for atomizing fuel oil comprising an upper and a lower chamber; means for supplying the oil to the upper chamber and steam under pressure or compressed air to the lower chamber; a grooved inclined floor on which the oil is distributed as a film; a lip at the edge of said floor over which the oil film can fall as a thin curtain; and a plurality of converging orifices in the front of the lower chamber below and behind the lip, through which orifices, jets of steam under pressure or compressed air are delivered to atomize the falling curtain of oil.
9. An apparatus for atomizing fuel oil, comprising an upper chamber with an open front; a lower chamber; means for supplying oil to the upper chamber and steam under pressure or compressed air to the lower chamber; a partition separating the said chambers and having a transversely cambered surface on which the incoming oil spreads as a film; transverse grooves on said surface, said grooves being deepest on the median line and becoming shallower towards each side; a lip at the front of said partition having a sharp downward curve; and a plurality of orifices in the front of the lower chamber forwardly converging in pairs towards points approximately vertical beneath the edge of said lip, through which orifices atomizing jets are delivered to atomize the thin curtain of oil falling vertically over the lip in front of said jets.
10. An apparatus for atomizing fuel oil, comprising an upper chamber with an open front; a lower chamber; means for supplying oil to the upper chamber and steam under pressure or compressed air to the lower chamber; a partition separating the said chambers and having an upper surface which forms a floor on which the incoming oil distributes itself as a film; a lip at the front of said partition having a sharp downward curve; and a plurality of converging orifices in the front of the lower chamber below and behind the lip adapted to deliver

atomizing jets of steam under pressure or compressed air against a thin curtain of oil falling in front of said jets.

11. An apparatus for atomizing fuel oil comprising an upper chamber with an open front; a lower chamber; means for supplying oil to the upper chamber and steam under pressure or compressed air to the lower chamber; a partition separating the said chambers and having an upper surface on which the incoming oil distributes itself as a film; alternating grooves and ribs on said surface; a lip at the front of said partition having a downward curve; and a plurality of orifices in the front of the lower chamber forwardly converging in pairs, through which orifices atomizing jets are delivered to atomize the thin curtain of oil falling over the said lip.
12. An apparatus for atomizing fuel oil, comprising a casting having an upper chamber with an open front end; a lower chamber; means for supplying the fuel oil to the upper chamber and steam under pressure or compressed air to the lower chamber; a partition separating the said chambers and having an upper surface on which the oil spreads as a film, grooves on said distributing surface; a lip at the front delivery edge of said partition over which the oil can fall as a thin curtain, and a plurality of converging orifices in the front of the lower chamber below and behind the said lip adapted to deliver atomizing jets against the thin curtain of oil falling in front of said jets.
13. An apparatus for atomizing fuel oil, comprising a casting having an upper chamber with an open front end; a lower chamber; means for supplying the fuel oil to the upper chamber and steam under pressure or compressed air to the lower chamber; a partition separating the said chambers and having a downwardly sloping upper surface on which the oil spreads as a film; corrugations on said distributing surface consisting of alternating grooves and ribs; a lip at the front delivery edge of said partition having a sharper downward curve; and a plurality of orifices in the front of the lower chamber converging in pairs towards points approximately vertically beneath the edge of said lip and adapted to deliver converging atomizing jets against the thin curtain of oil falling vertically over the lip in front of said jets.

14. An apparatus for atomizing fuel oil, comprising an upper chamber open at the front end; a lower chamber; means for supplying oil to the upper chamber and atomizing fluid under pressure to the lower chamber; a partition separating the said chambers, the upper surface of which forms a distributing surface on which the oil spreads as a film; a lip at the delivery edge of said partition over which the oil can fall as a

thin curtain; and a removable plate containing a plurality of converging atomizing orifices, said plate being adapted to be fastened to the front end of the lower chamber below and behind the lip.

15. An apparatus for atomizing fuel oil, comprising an upper and a lower chamber both fan-shaped in plan; means for supplying oil to the upper chamber and atomizing fluid under pressure to the lower chamber; a partition separating the said chambers, the upper surface of which forms a distributing surface on which the oil spreads as a film; a lip at the delivery edge of said partition over which the oil can fall as a thin curtain; and a removable plate containing a plurality of converging pairs of atomizing orifices, said plate being adapted to be fastened to the front end of the lower chamber below and behind the lip.

16. An apparatus for atomizing fuel oil, comprising an upper chamber open at the front end; a lower chamber; means for supplying oil to the upper chamber and atomizing fluid under pressure to the lower chamber; partition separating the said chambers the upper surface of which forms a distributing surface on which the oil spreads as a film, alternating grooves and ribs on said surface; a lip at the lower edge of said partition having a sharp downward curve over which the oil can fall as a thin curtain; and a removable plate secured to the front open end of the lower chamber and containing a plurality of rows of staggered orifices forwardly converging in pairs and adapted to deliver converging jets against the thin curtain of oil falling in front of said jets.

17. An apparatus for atomizing fuel oil, comprising an upper and lower chamber fan-shaped in plan; means for supplying oil to the upper chamber and atomizing fluid to the lower chamber, an inclined partition separating the said chambers the upper surface of which forms a distributing surface on which the oil spreads as a film; corrugations on said distributing surface consisting of alternating grooves and ribs which gradually become wider and flatter towards their lower end, a lip at the lower end of said partition having a sharper downward curve over which the oil can fall as a thin curtain; and a removable plate secured to the front open end of the lower chamber and containing a plurality of orifices forwardly converging in pairs and adapted to deliver converging jets against the thin curtain of oil falling in front of said jets.

18. An apparatus for atomizing fuel oil, comprising a casting having an upper chamber with an open front end; a lower chamber with an open front end; means for supplying oil to the upper chamber and steam under pressure or compressed air to the lower chamber; a partition separating the

- two chambers, the upper surface of which forms distributing surface on which the oil spreads as a film; alternating grooves and ribs on said distributing surface; a downwardly curved lip at the lower end of said partition over which lip the oil falls as a thin curtain in advance of the front of the lower chamber; a recess on the under side of said lip; a thickened part on the lower side 10 near the front of said partition; a transverse slot in said thickened part; a plurality of bosses on the front open end of the lower chamber; a removable plate the top of which takes into the said transverse slot and the 15 lower part of which is bolted to the bosses on the front of the lower chamber; and a plurality of converging pairs of orifices in said plate adapted to deliver atomizing jets against the oil curtain falling in front of 20 said jets.
19. An apparatus for atomizing fuel oil, comprising a casting having upper and lower open-fronted chambers, the floors of which are fan-shaped in plan; means for 25 supplying oil to the upper chamber and steam or compressed air to the lower chamber; a downwardly inclined fan-shaped partition separating the two chambers the upper surface of which forms a distributing 30 surface on which the oil spreads as a
- film, corrugations consisting of alternating grooves and ribs on a portion of said surface, which corrugations gradually become wider and shallower towards the lower end of said surface and finally disappear; a 35 downwardly curved lip at the lower end of said partition over which the oil film falls as a thin curtain in advance of the lower chamber; a recess on the under side of said lip; a thickened part on the lower side near 40 the front of said partition; a transverse slot in said thickened part; a plurality of bosses on the front end of the lower chamber; a removable plate transversely curved to the radius of the front of the lower chamber, 45 the top of which plate takes into the said transverse slot and the lower part of which is bolted to the said bosses and a plurality of converging pairs of orifices in said plate adapted to deliver atomizing jets against 50 the oil curtain falling in front of the said jets.

In witness whereof, I have hereunto signed my name this 20th day of December 1921, in the presence of two subscribing witnesses. 55
